UNITED STATES PATENT OFFICE.

ROBERT E. FRAME, OF ST. LOUIS, MISSOURI, ASSIGNOR TO AMERICAN CAR & FOUNDRY COMPANY, OF ST. LOUIS, MISSOURI, A CORPORATION OF NEW JERSEY.

COMBINED STAKE-POCKET AND SHAFT-BEARING.

No. 855,943.

Specification of Letters Patent.

Patented June 4, 1907.

Application filed April 4, 1907. Serial No. 366,343.

To all whom it may concern:

Be it known that I, ROBERT E. FRAME, a citizen of the United States, residing at St. Louis, Missouri, have invented a certain new and useful Improvement in Combined Stake-Pockets and Shaft-Bearings, of which the following is a full, clear, and exact description, such as will enable others skilled in the art to which it appertains to make and use the same, reference being had to the accompanying drawings, forming part of this specification, in which—

Figure 1 is a side elevation of a dump car provided with my combined stake pocket and shaft bearing; Fig. 2 is a cross sectional view taken through the side of the car; Fig. 3 is an enlarged cross sectional view of my improved device showing it in operative position; and Fig. 4 is a perspective view of the two members which constitute my improved device.

This invention relates to stake pockets, and particularly to the side stake pockets that are used on side door dump cars.

The object of my invention is to provide a combined stake pocket and shaft bearing which is so constructed that the side stakes can all be erected and the door-operating shaft can thereafter be arranged in place.

Briefly described, my improved device consists of a member for receiving a side stake and a shaft bearing member detachably connected to said stake member and secured in place by one of the devices that is used for connecting said stake pocket member to the car frame.

Referring to the drawings, 1 designates a side stake of a dump car provided with a side door 2 that is operated by a shaft 3 extending longitudinally of the car.

The device which represents the preferred form of my invention is shown in Figs. 3 and 4, and consists of a stake pocket member 4 and a shaft bearing member 5, detachably connected thereto. The stake pocket member is provided in its front wall with an opening 6 above which is an outwardly projecting portion 7, the inner side of which constitutes a shoulder or rib 8 that co-operates with a hook 9 at the upper end of the shaft bearing member 5, the upper end of said member 5 projecting into the opening 6 in the stake pocket member, as shown in Fig. 3. The

member 5 is provided with a portion 10 to receive the shaft 3, and the lower portion of 55 said member 5 is arranged between lugs 11 on the stake pocket member, said lugs being provided with grooves 12 that receive a U bolt 13, the shaft bearing member 5 also being provided at its lower end with a groove 60 11^a to receive this same U bolt.

At the upper end of the stake pocket member is a flange having a groove in which is arranged a U bolt 14 and when placing the device in position the stake pocket 4 is first secured to the side sill 15 of the car, as shown in Fig. 2, by means of this upper U bolt 14, all of the side stakes being erected and held in position in this manner. The longitudinally extending shaft 3 is then arranged in 70 place and the upper ends of the members 5 are inserted in the openings 6 in the stake pockets so that the hooks 9 on said members will engage the shoulders 8 on the front walls of the stake pockets, the lower U bolts 13 being then put in place and secured to the side sill 15 or other part of the car frame, thereby clamping the shaft bearing member to the stake pocket and also securely fastening the stake pocket to the frame of the car. 80

If desired, the members 4 and 5 can be assembled before the member 4 is placed in position to hold the stake so that when the shaft is to be put in place, the member 5 can be swung upwardly on the lip 8 as a fulcrum, 85 said lip and the hook 9 on the member 5 forming a pivotal connection between the members 4 and 5.

The stake pockets which have heretofore been in general use were so constructed that 90 the door-operating shaft had to be arranged in position at the same time the stakes were erected and this added greatly to the cost of constructing the car owing to the fact that a workman had to be stationed at each stake. 95 My improved device obviates this as the door-operating shaft is not arranged in position until after all the stakes have been erected.

Another desirable feature of my construction is that it enables the door-operating shaft to be removed at any time without taking down the side stakes. 100

Having thus described my invention, what I claim as new and desire to secure by Letters 105 Patent is:

1. A combined stake pocket and shaft bearing, consisting of a member for receiving a stake, and a shaft bearing member detachably connected to the stake pocket member; substantially as described. 65
2. A combined stake pocket and shaft bearing, consisting of a member for receiving a stake, and a shaft bearing member pivotally connected to the stake pocket member; substantially as described. 70
3. A combined stake pocket and shaft bearing, consisting of a member for receiving a stake, and a movable shaft bearing member carried by said stake pocket member; substantially as described. 75
4. A device of the character described, comprising a stake pocket member, a movable shaft bearing member carried by said stake pocket member, and means for securing said shaft bearing member in position; substantially as described. 80
5. A device of the character described, comprising a stake pocket member, a shaft bearing member carried by the stake pocket member and adapted to swing upon a horizontal axis, and means for securing said shaft bearing member in position; substantially as described. 85
6. A device of the character described, comprising a stake pocket member, a shaft bearing member arranged on the outer face of said stake pocket member and movable relatively thereto, and means for securing said shaft bearing member in position; substantially as described. 90
7. A device of the character described, comprising a stake pocket member provided in its front wall with an opening, a shaft bearing member having a portion which enters said opening and engages the inside face of the front wall of the stake pocket member, and means for securing said shaft bearing member in position; substantially as described. 95
8. A device of the character described, comprising a stake pocket member, a movable shaft bearing member carried by the stake pocket member, and means on the stake pocket member for preventing lateral movement of the shaft bearing member; substantially as described. 100
9. A device of the character described, comprising a stake pocket member, a shaft bearing member pivotally connected at one end to the front wall of the stake pocket member, and lugs on said stake pocket member between which the shaft carrying member is arranged; substantially as described. 115
10. A device of the character described, comprising a stake pocket member provided in its front wall with a transversely extending opening, a shaft bearing member having a portion which projects into said opening, and means for securing said shaft bearing member in position; substantially as described. 120
11. A device of the character described, comprising a stake pocket member provided in its front wall with an opening, a shaft bearing member provided at one end with a hook which enters said opening and engages a rib on the inside of the front wall of the stake pocket member, and means engaging the opposite end of said shaft bearing member for securing it in position; substantially as described. 125
12. A device of the character described, comprising a stake pocket member, means for securing said member to the frame of a car, a movable shaft carrying member connected at its upper end to the front wall of the stake pocket member, and a device extending across said shaft carrying member and secured to the frame of the car for locking said shaft carrying member in position; substantially as described. 130
13. A device of the character described, comprising a stake pocket member provided at its upper end with a groove to receive a U bolt which connects it to the frame of a car, a shaft bearing member provided at its upper end with a portion that projects into an opening in the front wall of the stake pocket member, grooved lugs on the stake pocket member between which the lower end portion of the shaft bearing member is arranged, and a U bolt extending across the shaft bearing member and arranged in the grooves of said lug and provided at its ends with nuts for securing it to the frame of the car; substantially as described. 135
14. A device of the character described, comprising a stake pocket member, and a movable shaft bearing member arranged on the front wall of the stake pocket member and secured in position by one of the devices which connects the stake pocket member to the frame of the car; substantially as described. 140
15. A car comprising side stakes, a hinged side door, stake pockets for securing said side stakes to the frame of the car, movable shaft bearing members mounted on the front walls of said stake pockets, a longitudinally extending door-operating shaft mounted in said shaft bearings, and means for retaining said shaft bearing members in position; substantially as described. 145

In testimony whereof I hereunto affix my signature in the presence of two witnesses, this second day of April, 1907.

ROBERT E. FRAME.
